TROLLING PLATE

Filed April 10, 1939

The diagram illustrates a mechanical assembly. At the top, a vertical pipe section labeled 'A' is connected to a horizontal tube. A curved pipe labeled '6' is attached to the horizontal tube. A valve assembly, labeled '5', is positioned between the horizontal tube and the curved pipe. A flexible hose, labeled '4', is attached to the valve assembly. A vertical pipe labeled '2' is connected to the flexible hose. A horizontal pipe labeled '8' is connected to the vertical pipe '2'. A small tube labeled '3' is also shown. The labels are distributed as follows: 'A' is at the top left; '6' is on the curved pipe; '5' is on the valve assembly; '4' is on the flexible hose; '2' is on the vertical pipe; '8' is on the horizontal pipe; and '3' is on the small tube.

TROLLING PLATE

Gustav A. W. Ehmke, Spokane, Wash.

Application April 10, 1939, Serial No. 267,046

3 Claims. (Cl. 115—0.5)

My present invention relates to improvements in trolling plates with special reference to that class used in connection with outboard motors for the propulsion of small fishing boats. It being well known that motors so used, even when throttled down to their slowest idling speed, propel the boat too fast for trolling for game fish.

The invention resides in a brace, or bracket preferably attached to, and depending from the anti-cavitation plate on the motor immediately above the propeller, in any suitable manner, depending on the construction of the motor. The shank of the brace or bracket depending downward and having lugs or ears laterally disposed, to which are hingedly attached the two halves of the trolling plate, held in normal position transversely of a longitudinal line through the boat, the said halves of the plate being directly in the rear of the propeller and normally parallel therewith, being maintained in that position by a spring, preferably of the coiled type, and the hinged connections to the brace. This position is also the trolling position.

When the motor is operating at high speed, the halves of the trolling plate open along a vertical line through the center, each half assuming a position with its inner, vertical edge cutting the water vertically, and the halves being thus parallel, form a double rudder and are maintained in this position by the force of the water on their faces, during which time the said spring is in tension, ready to return the said halves to their normal position upon accelerating the speed of the motor. The action of the trolling plate is entirely automatic, and responsive only to the speed of the motor and propeller, and being actuated by the amount of the force of the water from the latter as it impinges upon the face of the trolling plate.

Objects

The primary object of my invention is to provide a device that will reduce the speed of the boat from approximately four miles per hour, which, in many cases, is the slowest speed possible with a motor throttled down to idling speed, to a suitable trolling speed of approximately one mile per hour, or just sufficient to keep the fish lure moving, or the spinner rotating, to attract the fish.

A further object is to provide a device light in weight and economically produced.

Still another object is to produce a device that will not act as a brake against the motor except 55

when the latter has been throttled down to its lowest idling speed.

Drawing

5 In the accompanying drawing which is a part of this application, I have shown the best mode I have thus far devised for a practical application of my invention, and also a modified form of construction, together with a modified form 10 of their attachments to the motor, as indicated by the dotted lines in Fig. 1, but obviously, my invention is susceptible of embodiment in other forms than those illustrated and described herein, and I therefore consider and claim as my own 15 all such modifications and adaptations of the form of the device as fairly fall within the scope of the appended claims.

Referring to the drawing, in which the several parts are shown and designated by numerals, the 20 same numeral being used to designate the same part throughout the several views, and in which—

Fig. 1 is a side elevation of a fragmental portion of the rear of a boat having an outboard motor attached at the rear, and one embodiment 25 of my invention attached to the anti-cavitation plate of said motor, wherein the trolling plate is in normal, or trolling position.

Fig. 2 is a rear elevation of the device as attached to the anti-cavitation plate, as projected 30 from Fig. 1.

Fig. 3 is similar to Fig. 1 except that the trolling plate is shown open, or the halves have been 35 swung around parallel to each other, as when the motor and propeller are rotating at full speed.

Fig. 4 is an enlarged view, in perspective, of the preferred form of my invention with the right hand half of the trolling plate shown open.

Fig. 5 is an enlarged transverse section of the 40 assembled device taken on line 5—5 of Fig. 1.

Fig. 6 is also an enlarged transverse section through the depending brace, taken on line 6—6 of Fig. 1.

Figs. 7, 8, and 9 are enlarged views of a modified form of my invention, in which,

Fig. 7 is a side elevation showing the halves of the trolling plate hinged at their vertical center, with the spring vertically disposed.

Fig. 8 is a transverse section on line 8—8 of 50 Fig. 7.

Fig. 9 is a similar view through the brace only, and taken on line 9—9 of Fig. 7.

Description and operation

The preferred embodiment consists of a de-

pending brace, or shank 1 having hinge plates 2 integral therewith, and attaching means as 3 for attachment to the anti-cavitation plate A of the motor. Hingedly attached to said plates 2 are the hinge ears 4 and 5 of each half of 6 and 7 of the trolling plate, respectively; in the rear of each of said plate halves 6 and 7 and about midway between the hinge ears is attached the ends of a preferably coiled spring 12, disposed horizontally between the hinge pins 8 and the plate halves to maintain their faces in alignment as shown best in Fig. 5. The straight edges of the plate halves 6 and 7 are bevelled as at 9 to offer the least resistance to the water when both halves assume parallel relation to each other, as in Fig. 3, and one half as shown in Fig. 5.

The hinge plates 2 are provided at their outer extremities with projections 10, Fig. 6, to maintain the plate halves 6 and 7 in vertical, parallel relation to each other when open, as in the dotted lines in Fig. 5, it being understood that both plate halves 6 and 7 open simultaneously, but in opposite directions, and around separate hinge pins 8, the brace 1 being provided with a widened nose 11 to prevent kinking or distorting the middle coils of the spring 12.

In order to prevent the plate halves 6 and 7 from becoming out of line with their faces, a projection 13 is provided on each hinge plate 2 so that the bevels on these co-act with the correspondingly bevelled edges of the straight edges on the hinged plate halves. All front edges of the device are streamlined, to offer the least resistance to the water when the plate halves are in open position.

The embodiment shown in Figs. 7, 8, and 9 is different from the above only in the action of the spring and the number of hinges; the spring being vertically disposed around the single hinge pin, and subject to a torsional strain instead of the tensional strain of the embodiment shown in Figs. 1 to 6 inclusive.

The upper portion of the brace may be attached to the motor in any suitable manner, or as shown in Fig. 1 in full, or in the dotted lines by clamping to the depending tubes of the motor.

From the foregoing, the construction and oper-

ation of the modification shown in Figs. 7, 8, and 9 is obvious.

Having fully shown and described my invention in its objects, construction and operation, what I claim as new, and desire to secure by Letters Patent of the United States is:

1. A flat trolling plate mechanism adapted for use with motor-propellers for boats, consisting of a depending arm adapted for attachment to the motor-propeller frame, a bifurcated flat trolling plate, the halves of which are hingedly attached to said arm directly behind the propeller, and a spring connecting each of the halves of the trolling plate.

2. A flat bifurcated trolling plate mechanism for use in combination with an outboard motor for boats, having a supporting arm adapted for attachment to the outboard motor structure, hinge members on the arm, a flat trolling plate in halves, hinge members on each half for connection to the hinge members on the arm, a spring, the ends of which are attached to the halves of the plate to flexibly hold them in alignment across their front faces when not acted upon by a displacing force of water from a propeller driven by the motor.

3. A trolling plate mechanism of three major pieces consisting of an arm for attachment to a suitable place on a motor-propeller frame, a flat trolling plate in halves, and a spring, connecting said halves, said halves of the trolling plate being hingedly connected to said arm in such manner as to be of service as a trolling plate at reduced speed of the motor, or as a double and parallel rudder when the speed of the motor is increased, a spring attached at its ends to each of the halves of the plate to flexibly hold them in facial alignment across their faces under slow motor speed, a double bevelled projection on said arm and bevelled edges on the line of bifurcation of the plate halves to co-act with those on the projection on the arm to prevent overtravel in a forward direction and to offer the least resistance to the water when the plate halves are used as a double rudder.

GUSTAV A. W. EHMKE.
